XR D 7,314

DESIGN FOR FLOWER-STAND.

Design No. 7,314, dated March 31, 1874

UNITED STATES PATENT OFFICE.

JOSEPH E. MORRIS, OF MINNEAPOLIS, MINNESOTA.

DESIGN FOR FLOWER-STAND.

Specification forming part of Design No. 7,314, dated March 31, 1874; application filed May 31, 1873.
[Term of Patent 7 years]

To all whom it may concern:

Be it known that I, JOSEPH E. MORRIS, of Minneapolis, in the county of Hennepin and State of Minnesota, have invented a new Design for Flower-Stands, of which the following is a specification:

The nature of my design is fully represented in the accompanying photographic illustrations, to which reference is made.

A represents the main stationary standard, which has the configuration shown, and is supported by the legs B B ornamented and curved with scroll outlines, as appears in the

photograph. C C are arms supporting the disks f f, and revolving about the main standard by means of collars D D, and ornamented as shown.

What I claim as my invention, and desire to secure by Letters Patent, is—

A design for a flower-stand, substantially as shown and set forth.

JOSEPH E. MORRIS.
